DESIGN FOR A SOAP DISH

Charles A. Mosgrove, Waterbury, Conn., assignor to The Autoyre Company, Incorporated, Oakville, Conn., a corporation of Connecticut

Application April 11, 1933. Serial No. 47,755

Term of patent 7 years

To all whom it may concern:

Be it known that I, CHARLES A. MOSGROVE, a citizen of the United States, residing at Waterbury, county of New Haven, State of Connecticut, have invented a new, original, and ornamental Design for a Soap Dish, of which the following is a specification, reference being had to the accompanying drawing, forming part thereof.

Fig. 1 is a perspective view of a soap dish, showing my new design.

Fig. 2 is a top plan view thereof, and

Fig. 3 is a front elevation.

I claim:

The ornamental design for a soap dish substantially as shown.

CHARLES A. MOSGROVE.
